(57) **CLAIM**

The ornamental design for a display screen with transitional graphical user interface, as shown and described.

DESCRIPTION

FIG. 1 is a front view of a display screen with transitional graphical user interface having a first image; FIG. 2 is a front view thereof having a second image; and, FIG. 3 is a front view thereof having a third image.

The broken line drawing of a display screen and portions of the user interface forms no part of the claimed design. The subject matter in this patent includes a process or period in which an image changes into another image. This process or period forms no part of the claimed design.
